US0D1112466S

(12) **United States Design Patent** (10) **Patent No.:** **US D1,112,466 S**
(45) **Date of Patent:** **** Feb. 10, 2026**

(54) **CLOSING CAP FOR STAMPS**

(71) Applicant: **Trodat GmbH**, Wels (AT)

(72) Inventor: **Manfred Ortner**, Pennewang (AT)

(73) Assignee: **Trodat GmbH**, Wels (AT)

(**) Term: **15 Years**

(21) Appl. No.: **29/966,696**

(22) Filed: **Oct. 4, 2024**

(30) **Foreign Application Priority Data**

Apr. 8, 2024 (EM) 015056811-0004

(51) **LOC (15) Cl.** **19-02**

(52) **U.S. Cl.**

USPC **D18/18**

(57) **CLAIM**

The ornamental design for a closing cap for stamps as shown and described.

DESCRIPTION

FIG. 1 is a top side perspective view of a closing cap for stamps;

FIG. 2 is a front side elevational view thereof;

FIG. 3 is a left side elevational view thereof;

FIG. 4 is a rear side elevational view thereof;

FIG. 5 is a right side elevational view thereof;

FIG. 6 is a top side elevational view thereof; and,

FIG. 7 is a bottom side elevational view thereof.
The broken lines depict environmental structure that forms no part of the claimed design.

1 Claim, 7 Drawing Sheets
